UNITED STATES PATENT OFFICE.

GEORGE MILLIGAN, OF DAVENPORT, IOWA.

DESIGN FOR A PINCUSHION.

40,965.

Specification for Design.

Patented Nov. 1, 1910.

Application filed September 12, 1910. Serial No. 581,740. Term of patent 7 years.

To all whom it may concern:

Be it known that I, GEORGE MILLIGAN, a citizen of the United States, and a resident of the city of Davenport, county of Scott, and State of Iowa, have invented a new, original, and ornamental Design for Pincushions, of which the following is a specification, reference being had to the accompanying drawing, forming a part thereof.

The figure is a front elevation of a pin cushion showing my new design.

I claim:

The ornamental design for a pin cushion as shown.

In testimony whereof I have signed my name to this specification in the presence of two subscribing witnesses.

GEORGE MILLIGAN.
